CLAIM

The ornamental design for a clothes hanger handle, as shown and described.

DESCRIPTION

FIG. 1 is a frontal perspective view of a clothes hanger handle showing my design;

FIG. 2 is a complete front cross sectional view thereof;

FIG. 3 is a top view thereof;

FIG. 4 is a right side view thereof;

FIG. 5 is a rear view thereof;

FIG. 6 is a bottom view thereof; and,

FIG. 7 is a left side view thereof.

The broken line showing hangers and clothes in FIG. 1 is for illustrative purposes only and forms no part of the claimed design.

The broken line occurring on the handle and strap shown in FIGS. 1 and 3-7 denote stitching which is part of the claimed design.
